(57) **CLAIM**

The ornamental design for a wallet, as shown and described.

DESCRIPTION

FIG. 1 is a perspective view of an embodiment of a wallet, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is another perspective view thereof, shown in an open configuration in a condition of use.

The broken lines indicate unclaimed environmental structures. The broken lines on the surface of the wallet in FIG. 8 indicated unclaimed surface indicia.

1 Claim, 5 Drawing Sheets
